(57) **CLAIM**

The ornamental design for an air conditioner, substantially as shown and described.

DESCRIPTION

FIG. 1 is a front view of an air conditioner showing our new design;

FIG. 2 is a rear view thereof;
FIG. 3 is a left view thereof;
FIG. 4 is a right view thereof;
FIG. 5 is a top view thereof;
FIG. 6 is a bottom view thereof;
FIG. 7 is a perspective view thereof;
FIG. 8 is a front view of a second embodiment of the air conditioner;
FIG. 9 is a rear view thereof;
FIG. 10 is a left view thereof;
FIG. 11 is a right view thereof;
FIG. 12 is a top view thereof;
FIG. 13 is a bottom view thereof;
FIG. 14 is a perspective view thereof;
FIG. 15 is a front view of a third embodiment of the air conditioner;
FIG. 16 is a rear view thereof;
FIG. 17 is a left view thereof;
FIG. 18 is a right view thereof;
FIG. 19 is a top view thereof;
FIG. 20 is a bottom view thereof;
FIG. 21 is a perspective view thereof;
FIG. 22 is a front view of a fourth embodiment of the air conditioner;
FIG. 23 is a rear view thereof;
FIG. 24 is a left view thereof;
FIG. 25 is a right view thereof;
FIG. 26 is a top view thereof;
FIG. 27 is a bottom view thereof;
FIG. 28 is a perspective view thereof;
FIG. 29 is a front view of a fifth embodiment of the air conditioner;
FIG. 30 is a rear view thereof;
FIG. 31 is a left view thereof;
FIG. 32 is a right view thereof;
FIG. 33 is a top view thereof;
FIG. 34 is a bottom view thereof; and,
FIG. 35 is a perspective view thereof.
The broken line portions are included to show unclaimed subject matter only, and form no part of the claimed design.
